(57) **CLAIM**

We claim the ornamental design for an earphone case, as shown and described.

DESCRIPTION

FIG. 1 is a front perspective view of an earphone case showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a perspective view of the earphone case of FIG. 1 shown in an open position.

FIG. 9 is a front perspective view of another embodiment of an earphone case showing our new design;

FIG. 10 is a front view of FIG. 9;

FIG. 11 is a rear view of FIG. 9;

FIG. 12 is a left side view of FIG. 9;

FIG. 13 is a right-side view of FIG. 9;

FIG. 14 is a top plan view of FIG. 9;

FIG. 15 is a bottom plan view of FIG. 9; and,

FIG. 16 is a perspective view of the earphone case of FIG. 9 shown in an open position.

The broken line shown in FIGS. 1 through 11 and 14 through 16 is included for the purpose of illustrating portions of the earphone case that do not form a part of the claimed design.
